(57) **CLAIM**

The ornamental design for a pull-out storage basket, as shown and described.

DESCRIPTION

FIG. 1 is a front, left and top perspective view of a pull-out storage basket showing my new design;

FIG. 2 is a rear, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the portion labeled with numeric 9 in FIG. 1.

The dash-dash broken lines in the figures depict portions of the pull-out storage basket that form no part of the claimed design. The dash-dot-dash lines in FIGS. 1 and 9 depict the bounds of the enlarged view and form no part of the claimed design.
